UNITED STATES PATENT OFFICE

JOHN R. McDERMET, OF JEANNETTE, PENNSYLVANIA, ASSIGNOR TO ELLIOTT COMPANY, OF JEANNETTE, PENNSYLVANIA, A CORPORATION OF PENNSYLVANIA

METHOD AND APPARATUS FOR DESUPERHEATING STEAM

Application filed April 29, 1926. Serial No. 105,415.

The present invention relates broadly to the art of heat exchanging and more particularly to an improved method and apparatus for treating superheated steam by 5 means of which the superheat may be destroyed in an effective and uniform manner.

At the present time, it is not uncommon practice to deliver superheated steam from the more modern boiler installations. Not 10 infrequently a portion, at least, of such steam is utilized with apparatus which has constituted part of a standard installation which has been in use for many years. Such apparatus is frequently not adapted for the use 15 of high temperature superheated steam, partly perhaps, because the temperature of the superheated steam may injure some of the apparatus in processes where steam is utilized for heating and partly also because more or 20 less obsolete equipment as referred to, is not able to handle such superheated steam. In such cases the use of a desuperheater is imperative.

The present invention has for certain of 25 its objects the provision of an improved method and apparatus for effectively desuperheating steam, the invention contemplating the mixing of water with steam. Under these conditions, a portion of the 30 water so mixed with the steam is evaporated to an extent determined by the heat value of the superheat in the steam. The desuperheated steam then passes onward from the desuperheater at a temperature corresponding 35 to its pressure, but in an increased amount due to the destruction of the superheat and the evaporation of water used in the process.

It is a further object of the present invention to provide a control and a method of 40 control which is adaptable for use with desuperheaters generally and which is not limited in its utility to the construction and operation of any particular type of desuperheater.

45 In the accompanying drawings there are shown, for purposes of illustration only, two different embodiments of the present invention, it being understood that the drawings are more or less diagrammatic for purposes 50 of illustration only, and that they do not de-

fine the limits of the present invention, it being contemplated that changes in the construction and operation disclosed in the drawings may be made without departing either from the spirit of the present invention 55 or the scope of the broader claims. In the drawings,

Figure 1 is a diagrammatic side elevational view partly broken away and partly in section illustrating one embodiment of the invention, 60 and

Figure 2 is a view similar to Figure 1 illustrating another embodiment of the invention.

In approaching the problem of effectively desuperheating steam, it is necessary to bear 65 in mind the fact that the temperature of saturated steam is a function of its pressure, the temperature and pressure being in exact agreement with standard steam table values. In practical operation, however, there is no 70 such thing as a constant steam pressure, and in all commercial existing boiler lines the steam pressure is variable to at least some extent. It is obvious, therefore, that the temperature function related directly to pressure, 75 which in turn, is a more or less variable quantity, is not a function which can be effectively and satisfactorily utilized for obtaining the desired control of the desuperheating process. 80

In effecting a desuperheating operation it is necessary to admit sufficient water to destroy the superheat of the steam and reduce it to a saturated temperature, which temperature, as before pointed out, is a function 85 of a variable pressure. It becomes apparent, under these conditions, that with any method of controlling a desuperheater, while the result to be obtained is the control of the temperature of the steam and make it correspond to the saturated value of the pressure, this temperature function, the control of which is desired, cannot be utilized as an actuating medium. 90

The present invention involves, under these circumstances, the peculiar condition that while the temperature is the thing which is to be controlled, the control must be effected by means other than the temperature, and the 95

present invention contemplates an operation based upon such conditions.

As previously pointed out, the invention contemplates the destruction of superheat by means of mixing water with the steam under such conditions that saturated steam is delivered at a saturated temperature corresponding to the pressure, the operation of desuperheating involving the evaporation of a quantity of water in accordance with the heat value of the superheat destroyed. Also, the desuperheater under such conditions of operation does not deliver steam at a constant temperature, but at a temperature value variable in accordance with the steam pressure.

In Figure 1 of the drawings there is illustrated more or less diagrammatically, effective means not only for bringing water into contact with superheated steam, but also for controlling the supply of water by means other than the temperature, whereby saturated steam is delivered by the desuperheater at a temperature corresponding to the pressure of the steam. In the drawings there is illustrated a desuperheater 2 conveniently comprising a casing having a more or less complicated baffle arrangement 3 therein over which water is adapted to pass from an inlet 4 in contact with superheated steam supplied to the casing through an inlet 5. By reason of the contact of the steam and water under such conditions an effective heat interchange is made possible, the superheat of the steam is destroyed, and the steam leaves the desuperheater through the outlet 6 as saturated steam.

Arranged below the desuperheater is a receiver 7, which may be of any desired construction adapted to receive water from the desuperheater and, therefore, being in communication with the interior of the casing 2. The receiver is provided with a discharge 8, the flow through which is preferably controlled by a calibrated orifice 9 of such size as to discharge only a comparatively small amount of water continuously from the receiver space. It will be understood that with such an orifice the discharge of water will be a natural function of pressure differential between the receiver space and the region into which the water is discharged. This discharged water represents waste water which may be conveyed to any suitable point or otherwise utilized in any manner that may be desired. Its purpose is to secure the desired sensitivity of operation of the apparatus by the control of the supplied water, whereby saturated steam is delivered by the desuperheater at a temperature corresponding to the pressure of the steam.

Connected to the receiver 7 is a suitable float housing 10 containing a float of standard construction, not shown, suitably connected by linkage 11 to a float operated valve 12 in the inlet 4, whereby the float will be

effective for opening the valve 12 to admit more water as the level in the float chamber lowers and to admit less water to the desuperheater as the level in the float chamber rises. The float chamber may be connected in known manner to the interior of the desuperheater by means of a balancing connection 13, as well understood in the art, and may be provided with gauge glass 14 for visibly indicating water level conditions therein.

With a construction of the general nature referred to, operated in accordance with the present invention, there is contemplated a supply of desuperheating water which, for purposes of convenience, description and consideration, may be divided into two quantities, A and B. The quantity A represents that which is evaporated in the desuperheating process and passes from the casing of the desuperheater as steam, while the quantity B represents an additional amount discharged from the desuperheater into the receiver for the purpose of helping maintain the level in the receiver in opposition to the discharge through the orifice 9. The valve 12 will admit water to the desuperheater in accordance with the sum of these two quantities.

By reason of the orifice 9, a surplus of water may be delivered to the desuperheater and thence to the receiver and continuously discharged therefrom in accordance with the differential pressure between the receiver space and the region into which the discharge takes place, the surplus represented by the quantity B being, however, generally proportional to the amount delivered. The drain through the orifice therefore, insures a fluctuation in the water level within the receiver, which fluctuation represents a possible means of control of the desuperheating operation.

The quantity A supplied to the desuperheater and defined as being evaporated, necessarily varies according to the amount of superheat which it is necessary to destroy, and consequently, upon the saturated temperature of the steam delivered by the desuperheater and upon the initial superheat of the steam delivered to it as well as with the quantity of steam passing through the desuperheater. The quantity B, on the other hand, is a constant quantity drained through the orifice, thereby making the total quantity A and B variable as the quantity A varies. Inasmuch as the quantity B is proportional to the amount drained, the operation of the present device is secure. If it were not for this quantity drained the quiet water in the receiver would, in theory, establish a level which would be substantially unvariable, but which in practice would steadily increase until the entire device became flooded. The quantity B, therefore, makes the water level in the receiver variable and controllable and enables this variation in level to be utilized

through the float valve for varying the supply of water to the desuperheater.

Under the foregoing conditions of operation, the quantity A varies over a wide limit, the quantity A being arbitrarily selected by the desuperheater in accordance with its demand and the quantity B being rejected in the receiver to vary the water level and hence the load. Since the quantity B delivered to the receiver is interlinked with the quantity A evaporated in the desuperheating process, the level in the receiver will rise or fall depending upon the ratio of B to the amount of water discharged by the orifice. The level control device will, therefore be actuated and will in turn control the delivery to the desuperheater of a quantity of water A and B, the A component of which is variable with outside conditions beyond any control of the level device.

In Figure 2 there is indicated a generally similar form of desuperheating apparatus in which parts corresponding to the parts already described are designated by the same reference characters having, however, a prime affixed thereto. In the form of Figure 2 there is indicated a boiler level control device 10', which in the drawings is illustrated as comprising a tube which may be partially filled with water and partially filled with steam at the upper level, and operating through the volatility of an enclosed gas, as will be understood in the art through the connection 11' for operating the control valve 12'. This constitutes a conventional type of boiler regulation.

While the desuperheaters themselves as hereinbefore pointed out may be of any desired construction, they are herein illustrated as being of the general construction disclosed and claimed in my copending application, Serial No. 651,301, filed July 13, 1923.

Certain advantages of the present invention arise from the provision in a desuperheating apparatus of means for controlling the temperature of the saturated steam delivered thereby by means other than the temperature function.

Other advantages of the present invention arise from the provision of a desuperheating operation in which a total amount of water delivered to the desuperheater is divided into quantities, one of which is determined by the demand of the desuperheater and the other of which represents a means of control for the supplied water.

Still other advantages of the invention arises from the provision of a desuperheating installation embodying a receiver receiving water from a desuperheater and operative to continuously discharge a predetermined amount of water whereby a fluctuation in water level within the receiver is insured of such nature that it may be effectively utilized

as a control for the supplied water to the desuperheater.

I claim:

1. In a desuperheating apparatus, a desuperheater having a superheated steam inlet and a saturated steam outlet, means for supplying water to the desuperheater, a receiver communicating with the desuperheater and having a water inlet and a fixed water discharge materially smaller than the inlet, and means operable in accordance with level variations in the receiver for controlling the supply of water to the desuperheater.

2. In a desuperheating apparatus, a desuperheater having a superheated steam inlet, a saturated steam outlet, float operated means for maintaining a substantially constant temperature of the saturated steam delivered through said outlet and connections for continuously withdrawing an arbitrary water quantity from the desuperheater.

3. In the method of desuperheating steam, the steps comprising supplying superheated steam, supplying water to the superheated steam for desuperheating purposes, collecting a portion of the water so supplied, controlling the supply of water by the quantity collected for maintaining a substantially constant saturated steam temperature, and continuously withdrawing an arbitrary water quantity from the desuperheater.

4. In the method of desuperheating steam, the steps comprising bringing superheated steam and water into contact, collecting a portion of the water, controlling the amount of water by the amount collected for controlling the temperature of the steam and make it correspond to the saturated value of the pressure, and continuously withdrawing an arbitrary water quantity from the desuperheater.

5. In the method of desuperheating steam, the steps comprising bringing the superheated steam into contact with water divisible into a quantity representing that to be evaporated, and a second quantity arbitrarily determined, utilizing said second quantity for controlling the supply of water, and continuously withdrawing a quantity of water arbitrarily determined.

6. In the method of desuperheating steam, the steps comprising bringing the superheated steam into intimate contact with a supply of water, controlling said supply to provide a quantity representing that to be evaporated in the desuperheating process and a second quantity arbitrarily determined, utilizing said second quantity for varying the supply of water, and continuously withdrawing a quantity of water arbitrarily determined.

7. In the method of desuperheating, the steps comprising delivering to a desuperheater an amount of water to be evaporated in a desuperheating process plus an additional amount, draining such additional amount from the desuperheater to provide a variable

water level in connection therewith, delivering the superheated steam to the desuperheater and utilizing said variable level to control the supply of water to the desuperheater.

5. 8. In the method of desuperheating steam, the steps comprising supplying to a desuperheater an amount of water in excess of that required for the desuperheating operation, constantly draining a predetermined quantity of water from the desuperheater, and utilizing variations in level caused by differences between the amounts drained and the excess supplied for controlling the supply of water to the desuperheater.

15. 9. In the method of desuperheating steam, the steps comprising supplying superheated steam, supplying water to the superheated steam for desuperheating purposes, controlling the supply of water for maintaining a substantially constant saturated steam temperature, continuously withdrawing a less amount of water than that supplied, and utilizing the water corresponding to the difference between that supplied and the amount used and withdrawn for controlling the water supplied.

30. 10. In the method of desuperheating steam, the steps comprising bringing the superheated steam into contact with water divisible into a quantity representing that to be evaporated and a second quantity arbitrarily determined, utilizing said second quantity for controlling the supply of water, and continuously withdrawing from contact with the steam an amount of water substantially equal to said second quantity.

40. 11. In the method of desuperheating steam, the steps comprising bringing the superheated steam into contact with water divisible into a quantity representing that to be evaporated and a second quantity arbitrarily determined, utilizing the second quantity for controlling the supply of water, and continuously withdrawing a greater volume of saturated steam than the volume of superheated steam supplied.

50. 12. In the method of desuperheating steam, the steps comprising bringing the superheated steam into contact with water divisible into a quantity representing that to be evaporated and a second quantity arbitrarily determined, utilizing said second quantity for controlling the supply of water, and continuously withdrawing water as such at a rate materially slower than the rate of water supplied.

60. 13. In the method of desuperheating steam, the steps comprising supplying superheated steam, supplying water to the superheated steam for desuperheating purposes, continuously withdrawing a portion of the supplied water, controlling the supply of water in accordance with the excess between the supply and the amount required for controlling the 65 temperature of the steam and making it cor-

respond to the saturated value of the pressure, and passing the saturated steam to other connections.

In testimony whereof I have hereunto set my hand.

J. R. McDERMET.
